FUNCTIONAL TRANSLATOR FOR PRINTING TELEGRAPH MACHINES

George A. Graham and Harry W. Parmer, Ocean-
port, N. J.

Application May 17, 1938, Serial No. 208,416

20 Claims. (Cl. 178—27)

(Granted under the act of March 3, 1883, as
amended April 30, 1928; 370 O. G. 757)

The invention described herein may be manufactured and used by or for the Government for governmental purposes, without the payment to us of any royalty thereon.

5 This invention relates to printing telegraph machines and more particularly to functional translators or selectors and function performing devices for such machines.

10 The invention supplements our previous Patent No. 2,128,242, dated Aug. 30, 1938, and application Serial No. 102,178, filed September 23, 1936, which disclose an exactly synchronized printing telegraph system, and new features in printing telegraph mechanisms. The present invention 15 comprises functional translator mechanisms and function performing devices used with the mechanisms previously disclosed.

20 One of the main objects of the invention is to provide a printing telegraph machine functional translator or selector.

25 Another main object of the invention is to provide means responsive to electrical signalling for the selection of such printing telegraph machine functions as line feed, carriage return, and figures and letters shift.

Another main object of the invention is to provide means for the presentation of the selected functional members to power driven cam operation of the selected functions.

30 Another main object of the invention is to lock out the automatic carriage step forward mechanism whenever a function is selected.

Another main object of the invention is to provide a functional translator or selector operative in conjunction with a permutation disk or code disk translator.

35 Another main object of the invention is to employ the movement of pertinent stunt bars or selector bars of a permutation disk or code disk translator to operate cocked triggers releasing function selectors, the power for the performance of the selected function being derived from a prime mover and including power reset and spacing mechanism disengagement features.

40 Another main object of the invention is to associate all function selectors in one combined group coordinated to operate upon a common universal bar, the universal bar also acting to reset any or all selectors. This feature alone is very valuable in the art because all previous mechanisms scatter the function performing devices at random about the machine.

45 Another main object is to provide a functional selector as a complete and replaceable unit.

50 Other important objects will become apparent to those skilled in the art as the description proceeds.

55 The principles of the invention are illustrated in the embodiment depicted in the accompanying drawings, in which:

Fig. 1 is a schematic diagram of our printing telegraph machine and incidental circuits which, while previously disclosed in Serial No. 102,178, filed September 23, 1936, are necessary herein in order to describe later our additional mechanisms 5 comprising the functional translator and function performing mechanisms;

Fig. 2 is a front elevation view of our printing telegraph machine with the keyboard removed;

Fig. 3 is a side elevation view of our printing 10 telegraph machine including the functional translator and function performing mechanisms;

Fig. 4 is a bottom sectional view of our receiver or shuttle selector mechanism;

Fig. 5 is a sectional view of the track switch 15 of our receiver or shuttle selector mechanism;

Fig. 6 is a plan view of our selector transfer assembly;

Fig. 7 is a plan view of the permutation disk or code disk translator conjunctional with our 20 functional translator;

Fig. 8 is a detailed section of the permutation disk translator showing a stunt bar interactive with a selector bar of our functional translator;

Fig. 9 is a view of our carriage figures and 25 letters shifting mechanism;

Fig. 10 is a view of the gang cam group and levers which deliver the power stroke to the selected functions and resets the selectors; and

Fig. 11 is a graph of the operation of the gang 30 cam group throughout one complete revolution.

In Fig. 1, we represent schematically our printing telegraph machine terminated at the ground connection 2 and the line terminal L. The motor 223 drives shaft 135 continuously through 35 bevel gears 224 and 134. The gang cam group 130 is at rest because the driven positive clutch member 131 is held out of engagement with the driving clutch member 132 by the clutch arm 137 against the tension of spring 133. Bevel gear 225, likewise in continuous rotation, drives gear 166 through gears 226 and 227. The vertical shaft 211 is pinned to gear 166 and is also in continuous rotation.

The vertical shaft 211 transmits drive to two 45 friction clutches; one for the type wheel 152 at 206 and 207; and the other for the rotor of the shuttle selector 190, and through gear 228, the reed escapement and distribution shaft 165. The type wheel 152 is rotated from selected position 50 to selected position; the stoppage of the type wheel at a selected position being caused by the interference of the pertinent stunt bar 214, selected by the alignment of slots in the translator code disks 215, in the path of the type 55 wheel stop member 212. The rotation of the shuttle selector 190 and of the reed escapement and distribution shaft 165 depends upon the position of the reed 172, and its escapement yoke 175, with respect to the escapement pins 174a 60.

to 174f inclusive mounted on the escapement hub 174 which is pinned to shaft 165.

The reed 172 is clamped at 179 and, upon being released, vibrates between the dotted positions 172a and 172b in six half cycles of vibration from start to stop. The normal or start-stop position of the reed is at 172a under the latch 171 of the start-stop magnet 62.

The distributor 51 performs an automatic stop function in a local circuit on the reed start-stop magnet 62, switching the magnet from the control of the line relay 48 direct to battery at segment 60a and switching back to line relay 48 control at segment 60 during one revolution of distributor arm 58. The transmitting distributor 49, in the progression by reed escapement of the distributor arm 50 from segment 56 to segments 51, 52, 53, 54, 55 and return to segment 56, performs the function of step by step connection of the keyboard transmitting contacts 17, 18, 19, 20 and 21 to the line 1 through line relay 48.

The cams 243 and 244 on the extremity of shaft 165 in conjunction with the cam levers or arms 245 and 250, the link 253, the release-restore bar 256, and the keyboard universal bar 24 operating latch 260, perform the functions of release and restore of the transmitting contact levers 12, 13, 14, 15 and 16, the contact lever 22 being the start-stop feature which is normally held closed with respect to contact 23. The keys of the keyboard, of which one is shown as 32, operate to rock the code bars 25, 26, 27, 28 and 29 into marking or spacing positions in accordance with the permutations of the five equal unit code. The code bars 35 in turn set the contact pawls 267, 268, 269, 270 and 271, in marking or spacing positions with respect to contact levers 12, 13, 14, 15 and 16. Upon the release of bar 256 the contact levers under spring tension will either make contact, or 40 not make contact, with the transmitting contacts 17, 18, 19, 20 and 21, dependent upon whether or not a contact pawl is interposed in spacing position as shown in the figure.

The shuttle selector rotor 190 is in step-by-step relationship with the transmitting distributor arm 50 under the joint escapement action of reed 172 driving escapement yoke 175 to permit the progression of escape pins 174a to 174f, inclusive. The shuttle selector rotor 190 and stator 189 is shown in detail in Figure 4, and in Figures 2 and 3 in relationship with the selecting magnet 65 and its armature 66. The shuttle selector track switch and armature is shown in Figure 5. Suffice it to say that in one revolution of the rotor 55 190 the shuttle selectors 190a to 190e are assigned to either the marking track 189a or the spacing track 189b dependent upon whether the armature 66 is in marking or spacing position at the instant each particular shuttle selector passes 60 the armature at the track switch.

The code disk translator is shown in a detailed cross-sectional view in Fig. 2 at 213, the permutation disks or slotted code disks being 215 and the transverse members or stunt bars at 214. The 65 particular stunt bar at 214 is shown in selected position effecting the stoppage of type wheel 152 at the stop member 212.

The selector transfer assembly which transfers the established selection from the shuttle selector to operate upon the code disk translator at the proper time is the transfer frame 192 (Fig. 2) carrying the five transfer cams 192a to 192e. See also Fig. 6. Upon downward movement of the transfer assembly, the transfer cams 192a to 192e, 70 75 are set in marking or spacing positions as deter-

mined by the shuttle selectors 190a to 190e, and the transfer cams operate upon the push-pull bars 216a to 216e, to rotate the individual code disks toward marking or spacing positions. Upon the return to normal or upward movement of 5 the transfer assembly the operation is completed; that is, the code disk rotation into marking or spacing positions is completed. The V members shown on the bottom of the translator housing 213 directly above the transfer cams serve to cam 10 the push-pull bars into the completed movement. The selector transfer assembly in the down and up movement described performs another function; that is, of clearing or resetting the translator stunt bars 214 to a normal position 15 in the downward movement, and in releasing all stunt bars for the selection of one stunt bar in the upward movement, by means of the reset disk formed at the top of the transfer frame 192 acting upon the stunt bar extensions about pivot 218. 20 The transfer shift yoke arm is 193 (see Fig. 3) with pivot at 191.

Now in this invention we are mainly concerned in describing our function selecting mechanisms and function performing devices from the initial 25 selection at a given stunt bar in the code disk translator through the selection and performance of a given machine function, and the interaction of our previously described mechanisms.

The relationship of the functional translator 30 with the code disk translator is shown in plan view in Fig. 7, and a detailed view of the trigger action of a stunt bar of the code disk translator upon the functional translator is shown in Fig. 8. The pertinent members are also shown in a side 35 elevation view in Fig. 3. In Fig. 7 the function selecting stunt bars of the code disk translator are designated 214a, 214b, 214c, and 214d, which are assigned respectively to line feed, carriage return, letters shift and figures shift. In Fig. 8 40 the disposition of details is shown before a selection has been effected and in Fig. 7 after a selection has been effected.

In Fig. 8, 214d is the figures shift stunt bar, 279 is the trigger latch, and 283 is the action bar. 45 The trigger latch is held cocked in normal position by a compression spring. In this position the latch holds the action bar 283 in normal position. The code disks of the translator are 215 and the translator housing 213. Upon a proper 50 selective permutation of the code disks the stunt bar is drawn into an alignment of slots in the code disks, thereby thrusting the trigger latch 279 out from under the action bar 283 which moves down sharply under spring tension as shown in Figs. 3 55 and 7. Stunt bars 214a, 214b, and 214c operate in an identical manner upon trigger latches 276, 277 and 278, and the action bars 280, 281 and 282.

With reference to Figs. 3 and 7; 288, 289, 290 and 291 are connecting links between the action 60 bars 280, 281, 282 and 283, and the functional selectors 315, 316, 317 and 318 of the functional translator. Hence it will be seen that the functional selectors operate from a normal position at the right to an off-normal position to the left. 65 Operation of any one of the functional selectors throws a universal and reset bar 293 off-normal about pivot 292. The universal and reset bar 293 is equipped with an arm 294 which operates upon the carriage spacing lock-out lever 295; 70 i. e., operation of any functional selector locks out the automatic carriage spacing feature of the machine. Also the restore action of the universal and reset bar 293 upon the functional selectors, connecting links, action bars and trigger 75

latches, occurs at the proper time by means of cam 229 and cam lever 296, and removes the lock from the automatic carriage spacing feature.

- The line-feed functional selector 315 in operation to the left, under spring action, positions push rod 314 above the thrust lever 298. At the proper time the thrust lever 298 is raised under power drive through shaft 301 by means of the functional cam lever 297 and cam 320. Attention is invited at this time to the fact that the power for the performance of all functions is transmitted through this cam lever 297 and cam 320 each function being presented to the drive stroke by the functional translator selectors. The up stroke of the push rod 314 exerts a down thrust on the ratchet bar 322 through the lever 321. It will be noted that the construction of the ratchet bar permits free movement of the carriage across the face of the type wheel 152. The down stroke of the ratchet bar 322 and ratchet 324 rotates the ratchet wheel attached to shaft 141 which carries the paper roller 138. The dog 325 serves to prevent back slip.

In every printing operation the carriage is automatically spaced by the action of cam lever 232 upon arm 234 and ratchet 237 in engagement with rack 238, except when arm 234 is held normal and locked out by the carriage spacing lock-out lever 295 as the result of function selection. Each spacing operation builds up tension in the carriage return spring 160.

- The carriage return functional selector 316 in operation to the left, under spring action, positions push rod 319 above the thrust lever 298. Upward motion of the push rod 319 acts upon the finger 327, through arm 326 and a proper pivot, to disengage the holding dog and spacing ratchet 237 from the carriage rack 238, thus permitting the carriage to return to the "start of line" position under action of spring 160.

The letters shift functional selector 317 or the figures shift functional selector 318 in operation to the left under spring tension, positions a shift lever 300 to the left or right with respect to the pivot 300a. Reference is now made to Fig. 9. The shift lever 300 in turn moves a yoke 306 left or right. The yoke is connected to two legs 307 and 308 which are pivoted at 309 and 310 on the shift frame 311. The legs 307 and 308 present extensions to thrust levers 303 and 304. Hence as to whether or not the extensions of the legs are engaged by the thrust levers is determined by the position of the shift lever 300 which in turn is established by the letter shift functional selection 317 or the figure shift functional selector 318. The shift frame 311 is pivoted at 305 and is rocked into one of two positions upon the down stroke of the thrust levers. The shift frame sets the carriage 239 into letters or figures position, that is the paper roll 138 (Fig. 3) into letters or figures position with respect to the type wheel, by elevation or depression of the carriage about 240 by means of the connecting arm 312. The down stroke of the thrust levers 303 and 304 occurs at the proper time as transmitted by cam 320 (Fig. 3) through cam lever 297 and shaft 301 (Fig. 7). In Fig. 7 the selection is shown made for figures shift and in Fig. 9 the selected function of figures shift is shown performed.

Reference is made to Figs. 1, 3, 10, and 11. The gang cam group assembled upon the tubular sleeve 130 is normally at rest but, upon the completion of the processes of transmission, reception, and selection, is permitted to rotate one

complete revolution by the timed engagement of the driven clutch member 131 with the driving clutch member 132 which is connected by shaft 135, gear 134, and gear 224 to the drive of motor 223 (Fig. 1). Cam 231 operates upon the ribbon feed mechanism, the details of which are not shown herein. Cam 129 operates upon the devices which transfer a selection from the shuttle selector to the code disk translator and release and reset the stunt bars thereof. Cam 230 operates upon the printing and automatic carriage spacing devices. Cam 320 transmits power at the proper time for the machine operations of line feed, carriage return, letters shift, and figures shift, upon the pertinent selection of any one of these functions by the functional translator. Cam 229 removes the carriage space lock-out, and restores the selectors of the functional translator to normal, recocking the selected trigger latch in normal position. A graphical representation of the relation of the cams through one revolution of the group is shown in Fig. 11.

Now let us consider a typical example of operation throughout from the transmission of a desired function, by keyboard operation at one station, to the performance of this function at the local and distant station. Let us assume it is desired to transmit, and effect the performance of, the figures shift function. In our signalling code the figures shift function is assigned as 1 marking, 2 marking, 3 spacing, 4 marking and 5 marking. Reference is made to Fig. 1 representing a local machine connected by line and ground return to an identical distant machine. In the normal state the motor 223 is operating and shafts 135 and 211 are in continuous rotation with the type wheel at rest, its friction clutch slipping, and the shuttle selector rotor 190 and escapement shaft 165 at rest with friction clutch slipping, the reed 172 being latched in position 172a and hence holding shaft 165 from rotation by the engagement of the escapement yoke 175a under escapement pin 174a. The line circuit is closed in normal state at the start-stop contacts 22 and 23, the circuit being from battery 3, wire 4, contact 23, contact lever 22 closed, wire 11, wire 10, line relay 48, line wire 1, through an identical circuit at distant station including poled battery and return at ground 2 to battery 3. The line relay contacts hold the selector magnet 65 in marking position in a local circuit, and also hold the reed magnet 62 energized in a parallel local circuit through distributor 57. The gang cam group 130 is at rest being disengaged from drive at clutch member 131.

The figures shift key 32 is now depressed setting up the code combination 1, 2, 4, and 5 marking, and 3 spacing, of the code bars 25, 26, 27, 28, and 29, and the contact pawls 267, 268, 269, 270, and 271, as shown in Fig. 1. The universal bar 24 is also operated which by the withdrawal of latch 260 releases the transmitting contact release-restore bar 256 to open the start-stop contact lever 22 from contact 23, and permit contact levers 12, 13, 15 and 16 to close with respect to contacts 17, 18, 20 and 21, the contact lever 14 being held open with respect to contact 19 by interference of pawl 269 in spacing position.

The removal of contact lever 22 from contact 23 opened the line circuit releasing the line relay 48 and in turn the selector magnet 65 and the reed magnet 62. The reed 172 is released from position 172a to vibrate in its natural period to position 172b and back to 172a in six half

cycles of vibration thus permitting the progression of the escapement shaft 165, distributor arms 59 and 58, and the shuttle selector rotor 190 in six successive steps as determined by the action 5 of the reed-driven escapement yoke 175 upon the escapement pins 174a, 174b, 174c, 174d, 174e and 174f. In this process the distributor arm 59 of the transmitting distributor consecutively connects the transmitting contacts to line and transmits the code signals 1, 2, 4, 5 marking and 3 spacing, the local and distant line relay operating accordingly. At the distant station the start-stop contact combination 22-23 remains closed with the distributor at that station shorted out of the 10 line circuit by wire 11. The line signal performance is transferred by the line relay contacts to actuate the selecting magnet 65 in the local circuit at each station, which in the rotation of the shuttle selector rotor 190 in six successive steps, 15 sets the selecting shuttles 190a, 190b, 190c, 190d, and 190e in the coded marking-spacing positions.

In the fifth progressive step of rotation of the escapement shaft 165, the reed start-stop magnet 65 is energized locally at each station through 20 distributor segment 60a in readiness to catch the reed 172 upon return to position 172a in the sixth or last half cycle of vibration. The escapement shaft 165 in the sixth progressive step of rotation presents cam 187 to operate the clutch lever 137 permitting the engagement of clutch member 131 to the drive of clutch member 132 and hence 25 the gang cam group will rotate one full revolution. The escapement shaft 165 is stopped at pin 174a, the initial or starting position, and the shuttle selector rotor 190 stops also at the starting 30 position. The transmitting contact release-restore bar 256 is restored, by the cam and lever mechanism at the extremity of shaft 165, thus opening all transmitting contacts, closing the 35 start-stop contacts, and restoring the keyboard to normal. The start-stop magnet 62 is also returned to the control of the line relay through distributor segment 60, the magnet remaining 40 energized holding the reed because the line circuit is now closed at contacts 22-23.

As stated above the gang cam group 130 now 45 performs one full revolution. In this revolution the five cams, 231 ribbon feed, 129 selector transfer, 230 print and space, 320 functional performance, and 229 functionals selector reset, operate upon the respective cam levers in the relationship shown in Fig. 11, see also Fig. 3. During the first 50 45 degrees of revolution of the cams the selector transfer is operated, the function cam 320 falls off from previous operation, and the functionals selector reset cam 229 operates to restore any function selectors that may have operated previously. The selector transfer cam 129 elevates cam lever and rod 188 to pivot the transfer yoke 55 193 about 191 and depress the transfer frame 192. This action resets the last selected stunt bar 214 of the translator 213 to normal by means of the reset disk on the transfer frame; and presents the transfer cams 192a, 192b, 192c, 192d and 192e 60 to receive the selection established by the shuttle 65 selectors 190a, 190b, 190c, 190d and 190e, the movement of the transfer cams acting through the push-pull bars 216a, 216b, 216c, 216d and 216e to start the rotation of the code disks 215 70 into the selected marking-spacing positions. See also Fig. 2. The selector transfer cam 129 in fall off permits the return to normal of the cam lever and rod 188 under spring action, (similar to the spring shown in Fig. 10) and hence returns the 75 transfer frame 192 to normal. This action com-

pletes the rotation of the code disks into the selected marking-spacing positions, and releases all stunt bars 214 for one to fall into an alignment of slots in the code bars, which, in our assumption is the figures shift stunt bar 214d in Figs. 7 and 8. 5 Between stunt bar reset and stunt bar select the type wheel 152 rotates the angular distance between the pertinent stunt bars and hence now stops in the position with stop member 212 against stunt bar 214d. Incidentally, at this stop 10 position of the type wheel, the type bar presented to the subsequent printing action is blank and will cause no impression on the paper. The same is true for the positions at stunt bars 214a, 214b and 214c; i. e., selection positions for line 15 feed, carriage return, and letters shift.

The figures shift stunt bar 214d is shown in normal position in Fig. 8. This stunt bar is drawn into the alignment of slots in the code disk translator by an individual spring about pivot 218. 20 The stunt bar in movement trips the trigger latch 279 from beneath the extension pin or lug of the action bar 283 permitting this bar to snap down, under spring action on the figures shift selector 317 through the connecting link 291 25 which is pivoted at 287. See Figures 3 and 7 which show the operated positions of the details. The functional translator universal bar 293, upon being cleared by cam 229 after 180 degrees of rotation (Fig. 11), is thrown off normal which 30 rotates the carriage spacing lock out lever 295 to interfere with the subsequent action of the carriage spacing lever 234. The figures shift selector 317 in movement to the left rotates the shift lever 300 about pivot 300a to thrust the yoke 306 35 into the position shown in Fig. 9, presenting the extension on leg 308 beneath thrust lever 304. Upon the rotation of the functionals cam 320 to 270 degrees this cam in the final 90 degree rotation transmits motor power to elevate cam lever 40 297 and depress the thrust lever 304 to rotate the shift frame 311 about pivot 305 and set the carriage into the figures printing position with respect to type wheel as shown in Fig. 9. See 45 also Fig. 3.

Upon the completion of 360 degrees of rotation of the gang cam group, clutch 131 is disengaged from the drive of clutch 131 by the clutch lever, and cam 137 and the printing and spacing cam 230 operates to deliver a printing stroke to print 50 hammer 154; but as stated above the type wheel is blank in the figures shift position and no impression is caused on the paper. Also the spacing lever does not function being held out by lock out 55 arm 295.

The restoration to normal of the figures shift selector 317 occurs in the next revolution of the gang cam group, through 45 degrees rotation of cam 229 operating upon the universal bar 294, 60 which action also clears the spacing lockout. The figures shift frame 311, carriage 239 and associated details including shift lever 300 remain in the figure shift position for pertinent printing until the letters shift selector 318 is operated as 65 a result of selection.

It will be apparent to those skilled in the art that the invention presents numerous possibilities for extensions and adaptations well within its scope; as for example, the utilization of the 70 same mechanism which locks out the carriage step forward devices upon a function selection to also lock out the print hammer from performing the print stroke; and the utilization of the functional translator selecting members to oper- 75

ate electrical contacts in a motor start-stop circuit.

Changes, modifications, and equivalent arrangements are contemplated within the scope of the invention as defined by the appended claims.

We claim:

1. In a printing telegraph machine comprising means for the transmission and reception of code combinations of electrical signals, and including a code disk translator having a plurality of slotted disks with transverse stunt bars arranged to fall into an alignment of slots as a result of predetermined selection; a functional translator mechanism and means interactive through said stunt bars upon said mechanism when certain of said stunt bars fall into an alignment of said slots to effect the operations of selection and thereby control the performance of machine functions.
2. In a printing telegraph machine comprising means for the transmission and reception of code combinations of electrical signals and including a code disk translator provided with thrust members, and having a plurality of slotted disks with transverse stunt bars arranged to fall into an alignment of slots as a result of predetermined selection; a functional translator mechanism, and means interactive through said stunt bars upon said mechanism when certain of said stunt bars fall into an alignment of said slots to selectively present one of said thrust members to operate upon machine functions such as line feed, carriage return, and figures and letters shift.
3. In a printing telegraph machine comprising means for the transmission and reception of code combinations of electrical signals and including a code disk translator; a plurality of trigger cocked selecting members released by said code disk translator to select a plurality of machine functions; means for the performance of said machine functions upon selection; and means for recocking said selecting members to normal position.
4. In a printing telegraph machine comprising means for the transmission and reception of code combinations of electrical signals and including a code disk translator provided with transverse members; a functional translator comprising a plurality of selectors for differentiating between function performing mechanisms, and trigger members for holding said selectors normal; means for tripping said trigger members and releasing said selectors upon operation of the transverse members of said code disk translator; means for the application of power to said function performing mechanisms; and means for restoring said selectors to normal with respect to said trigger members.
5. In combination a code disk translator, a plurality of slotted code disks and a plurality of transverse members, said translator being selective to permuted settings of said code disks with respect to said members; a functional translator comprising a plurality of selecting members in trigger relationship with said transverse members; and means for releasing said selecting members under the control of said transverse members.
6. In combination a code disk translator, a plurality of slotted code disks and a plurality of transverse members, said translator being selective to permuted settings of said code disks with respect to said members; a functional translator comprising a plurality of selecting members un-

der spring tension and held in a normal position while said transverse members are in normal position; means for releasing said selecting members off normal by the action of said transverse members off normal; and means for restoring said transverse members and said selecting members to normal independently.

7. In combination a code disk translator, a plurality of slotted code disks and a plurality of transverse members, said translator being selective to permuted settings of said code disks with respect to said members; a plurality of thrust members; a functional translator comprising a plurality of selecting members under spring tension and held in a normal position while said transverse members are in normal position; a source of power and drive operative therewith; means for releasing said selecting members individually by the action of said transverse members to position a selected one of said thrust members for connecting said power drive to a desired mechanism; and means for restoring the said selecting member and disconnecting said thrust member from power drive.

8. In combination a code disk translator, a plurality of slotted code disks and a plurality of transverse members, said translator being selective to permuted settings of said code disks with respect to said members; a plurality of thrust members; a functional translator comprising a plurality of selecting members acting under spring tension and held in a normal position while said transverse members are in normal position; a power drive; means for releasing said selecting members individually by the action of individual transverse members to position a selected one of said thrust members for connecting power drive to a desired mechanism and for removing power drive from other normally connected mechanisms; and means for restoring said selecting member to normal, disconnecting said thrust member from power drive, and reconnecting power drive to said normally connected mechanisms.

9. In a printing telegraph machine, means responsive to electrical signalling for the selection of such functional mechanisms as line feed, carriage return, and figures and letters shift, comprising a receiving selector mechanism, a transfer mechanism, and a functional translator mechanism provided with latches; a code disk translator mechanism operative upon said latches; a power drive, and a cam and lever system operative therewith and with said mechanisms; and means coordinating said mechanisms to subject said functional mechanisms to the power drive under control of said cam and lever system and dependent upon the selection of said functional translator mechanism.

10. In a printing telegraph machine, means responsive to electrical signalling for the selection of such functional mechanisms as line feed, carriage return, and figures and letters shift, said means including a receiving selector mechanism, a transfer mechanism and a functional translator mechanism; a plurality of thrust members; a code disk character translator including stunt bars for selectively operating said last named mechanism; a power drive, and a cam and lever system operative with said drive and said mechanisms; and means for coordinating said mechanisms and whereby said functional mechanisms are brought into proper operative relationship with said power drive under cyclic control of said cam and lever system, and dependent upon the selection of said functional translator

mechanism acting in response to a direct release action of said thrust members controlled by trigger action of the stunt bars of said code disk character translator.

5 11. In a printing telegraph machine, means responsive to electrical signalling for the selection of such functional mechanisms as line feed, carriage return, and figures and letters shift, said means including a receiving selector mechanism, 10 a plurality of thrust members; a transfer mechanism, and a code disk translator mechanism comprising a plurality of cocked trigger members controlling said thrust members and a power drive; a functional translator; mechanism operative 15 in response to said code disk translator mechanism; means coordinating said mechanisms to present said thrust members to said power drive; and means for restoring all elements to normal.

20 12. In a printing telegraph machine comprising means for the transmission and reception of code combinations of signalling conditions, and including a selector mechanism; a functional translator provided with thrust members subject 25 to trigger action; a code disk translator operative upon said thrust members; a type wheel, and a pivoted paper carriage operative with said drive; a shift yoke and a pair of legs operative therewith and with said lever system; means comprising a 30 pivoted shift lever operative into one of a plurality of angular positions by said thrust members of the said functional translator to bring said yoke into operative position; and means comprising a shift frame and including a lever 35 connection to said paper carriage for the elevation or depression of the carriage into figures or letters printing position with respect to said type wheel as determined by the position of said pivoted shift lever and said shift yoke and legs 40 through the selective setting of said thrust members of the functional translator.

13. In a printing telegraph machine comprising transmitting and receiving means, a slotted code disk translator, a type wheel, a paper carriage and spacing mechanism normally spaced as 45 the result of printing action; means including a functional translator and a universal bar, said functional translator being selectively operated by said code disk translator to place said universal bar in off normal position upon any selection 50 in the functional translator; and means comprising a lock out mechanism to prevent carriage spacing upon the operation of said universal bar.

14. In a printing telegraph machine comprising transmitting and receiving means, a slotted code disk translator equipped with transverse selecting bars, a type wheel, a paper carriage, a paper roller, and line feed mechanism operative to advance said roller; and means comprising a 55 functional translator selectively receptive to resultants of operation of said code disk translator and through the off-normal action of a particular one of said transverse selecting bars to present power drive for the actuation of said line feed mechanism.

65 15. In a translator comprising a plurality of slotted code disks and including transverse members, said translator being adapted in permutations to select one of a plurality of said transverse members; a set of secondary selectors and a plurality of slide guided trigger members positioned as latches with respect to said selectors; means for releasing said secondary selectors upon

the selection of said transverse members, and thrust members presented by said secondary selectors to power drive for functional operations; and means for the restoration to normal thereof.

5 16. In a translator comprising a plurality of slotted code disks adapted in permutations to select one of a plurality of transverse members; a plurality of slide guided trigger members positioned as latches with respect to secondary selectors; and means for releasing said secondary selectors upon the selection of said transverse members to operate contacts in an electrical circuit.

10 17. In combination with a cylindrical slotted code disk translator comprising a plurality of code disks and a plurality of transverse selecting bars arranged radially about the vertical axis of said translator, certain of said transverse selecting bars acting as character-selection bars and others as function-selection bars; trigger latches 15 arranged in guide extensions of said function-selection bars and spring-tensioned thrust members normally held in restraint by said latches; and means for releasing a selected one 20 of said thrust members for function performance 25 of an intermediate thrust member under motor drive upon operation off normal of said function-selection bars.

30 18. In a printing telegraph machine including a translator comprising a plurality of slotted code disks and transverse members, said translator being adapted in permutations to select one of a plurality of said transverse members; a set of secondary selectors and a plurality of slide-guided trigger members positioned as latches 35 with respect to said selectors; means for releasing said secondary selectors upon the selection of said transverse members; and thrust members presented by said secondary selectors to power drive 40 for machine functional operations including bell signals; and means for the restoration to normal thereof.

45 19. A structure as set forth in claim 18, wherein the said thrust members presented by said secondary selectors to power drive for machine functional operations include a motor and a thrust member for opening the circuit of said motor, said thrust member being connected to said power drive and functioning to stop said motor as a result of translator selection.

50 20. In combination, a stop-at-print type wheel, and a cylindrical slotted code disk translator comprising a plurality of code disks and a plurality of transverse selecting bars arranged radially about the vertical axis of said translator, certain 55 of said transverse selecting bars acting as character-selection bars and others as function-selection bars; trigger latches arranged in guide extensions of said function-selection bars and spring-tensioned thrust members normally held 60 in restraint by said latches; means for stopping said type wheel at each one of said transverse selecting bars in off normal or selected position for character printing in character-selected position, no printing being effected in functional selected position; and means for releasing a selected one of said thrust members for function performance 65 of an intermediate thrust member under motor drive upon operation off normal of said function-selection bars.
